UNITED STATES PATENT OFFICE.

THOMAS S. WHEELWRIGHT, OF HIGHLAND PARK, ILLINOIS.

SEAL-LOCK.

SPECIFICATION forming part of Letters Patent No. 695,513, dated March 18, 1902.

Application filed March 15, 1899. Serial No. 709,145. (No model.)

To all whom it may concern:

Be it known that I, THOMAS S. WHEELWRIGHT, a citizen of the United States, residing at Highland Park, in the county of Cook and State of Illinois, have invented a certain new and useful Improvement in Seal-Locks, of which the following is a full, clear, concise, and exact description, reference being had to the accompanying drawings, forming a part of this specification.

My invention relates to seal-locks more particularly designed for use in connection with cars, but equally applicable to other purposes, my object being to provide a novel and effective form of seal-lock adapted to be employed in connection with a breakable seal.

In accordance with my invention I provide in connection with my seal-lock a seal formed of brittle material, as clay or the like, which can be readily broken, when desired, and I provide the seal in the shape of an elongated body adapted to be secured at the ends in the lock and carrying upon the sides or faces the necessary printed matter, which is applied to the seal. I preferably form the seal with openings in the ends, with which locking pins or lugs are adapted to engage to lock the seal in position. The lock of my invention in its preferred form comprises a pair of seal-holding devices adapted to interlock with the opposite ends of the seal, these seal-holding devices usually taking the form of pins or lugs adapted to enter openings provided in the opposite ends of the seal. The seal-holding devices are capable of a movement toward and from each other to accommodate the placing of the seal in position and are also capable of a relative movement laterally for the purpose of opening the lock, whereby upon opening the lock the breaking of the seal is insured. One of the seal-holding devices I have usually mounted in a stationary position upon the lock, while the other seal-holding device is carried upon a plunger adapted to be locked in its inner position to hold the seal in place, the plunger being unlocked and capable of movement into its outer position when rotated, this rotation serving to break and destroy the seal.

I have illustrated my invention in the accompanying drawings, in which—

Figure 1 is a view of the seal and lock of my

invention. Fig. 2 is a sectional view thereof. Fig. 3 is a sectional view on line 3 3, Fig. 2. Fig. 4 is a view of a modification of the lock. Fig. 5 is a detailed view of the seal. Fig. 6 is a view of a modification.

Like letters refer to like parts in the several figures.

In the form of my invention illustrated in Fig. 2 a barrel a is provided, which is secured to the car in any convenient manner—as, for instance, by a shank b , passing through the car-body and secured by a bolt b' . Within the barrel is a plunger c , above which is a coiled spring c' , which serves to impart to the plunger a downward tendency. The plunger is provided with a slot c^2 , with which a dog c^3 is adapted to engage, the dog being pressed into engagement by a coiled spring c^4 . A head c^5 is provided upon the end of the plunger to limit its downward movement. When the plunger is rotated within the barrel, the dog c^3 is moved backward and out of engagement with the slot, and the plunger being thus released the spring c' serves to move the same downward until the further movement is limited by the engagement of the head c^5 with the dog c^3 . At the lower end of the plunger a lateral arm c^6 is provided, which carries a locking pin or lug c^7 . A lateral arm a' is provided at the upper end of the barrel a , which carries a corresponding locking pin or lug a^2 . A seal d of triangular cross-section and provided with a longitudinal bore is adapted to be locked in position between the arms $a' c^6$ by the engagement of the locking-pins $a^2 c^7$ with openings or holes provided in the end of said seal. The seal is formed of clay or other similar brittle and easily-broken material, and when the seal is in position, as shown in Fig. 2, the plunger is locked in its inward position, and the seal is thereby locked between the pins $a^2 c^7$, and the seal cannot be removed nor can the plunger be moved into its outward position without first destroying the seal. The hasp e passes over the staple a^3 , and as the inner face of the seal rests in contact with or a short distance from the end of the staple a^3 the hasp cannot be removed from the staple until the seal is removed from its position.

To unlock the car, therefore, it is necessary to break the seal, and this in practice is usu-

ally done by moving the pin c^7 laterally by rotating the plunger, usually by grasping the lateral arm c^6 and forcing the same to one side. This movement fractures the seal d and completely destroys the same, so that its further use is prevented. When it is desired to place a new seal in position, the plunger is moved to its outer position and the seal placed between the pins a^2 c^7 , and then the plunger is thrust inward to lock the same, thereby locking the seal in position. Instead of employing locking-pins adapted to fit into openings provided in the ends of the seal any other desired form of seal-holding devices may be employed for securing the seal in position at the ends; but I preferably employ the construction illustrated, wherein longitudinal openings are provided in the ends of the seal in which locking-pins are adapted to rest. Since the seal is thus broken by means of pressure applied from within, a more complete shattering of the seal is secured, and the liability of the seal to break in a manner which would permit of the pieces being placed together again is entirely removed. As shown in Fig. 5, the name of the road may be printed upon one of the three faces of the seal, while the number of the seal may be placed upon the other face, the third face being adapted to rest against the staple to prevent the removal of the hasp. The openings in the ends of the seal are preferably of a non-symmetrical cross-section and are made to conform to locking-pins of similar cross-section, whereby the seal can be placed in only one position. This can be accomplished by making, for instance, a triangular hole with two of the faces plane, while the the third is curved. This insures the placing of the seal in position with the printed faces toward the front.

The lock above described is particularly adapted to be fixedly secured to the car.

In Fig. 4 I have illustrated a form of lock adapted to be used with hasps and staples of the class now commonly in use, wherein a pin is supported from a chain and is adapted to be placed through the staple. In this modification the barrel a carries at the upper end the arm a' , upon which is supported a locking-pin a^2 , and the plunger c is mounted within the barrel in the manner above described, with a lateral arm c^6 carrying the locking-pin c^7 . The barrel also carries a lateral arm a^4 , having upon the end a pin a^5 , adapted to be inserted through the staple, and in order to prevent the removal of the pin a lateral arm c^8 is provided at the end of the plunger adapted to rest opposite the end of the pin a^5 when the seal is in position. The seal is placed between the locking-pins a^2 c^7 in the manner above described, and the staple-pin a^5 is locked in position until the plunger is rotated, and this rotation necessitates the breaking of the seal.

In Fig. 6 I have illustrated a modification

in which the shank b^2 is threaded and adapted to be screwed into an opening provided in the car-wall, while the upper end of the barrel a carries a lug b^3 , through which a screw or nail may be passed to secure the lock 7^0 against turning. When it is desired to use the lock with the usual metal seals, the metal strip may be passed through the slots a^6 and a^7 , as shown in this figure, and the hasp is thus locked in position until the seal is broken. 75 Moreover, the record on the seal is by this arrangement effectively maintained in a visible position. The lock may thus be used interchangeably with the breakable seal and with the ordinary metal seal. 80

Having described my invention, what I claim as new, and desire to secure by Letters Patent, is—

1. In a seal-lock, the combination with a barrel carrying a seal-holding device, of a second seal-holding device adapted to coöperate therewith to hold a breakable seal in position, said second seal-holding device being mounted upon a part which is adapted to rotate relatively to said barrel and which is adapted to be moved longitudinally relatively thereto, and a lock for holding said part in position to maintain the seal in the locked position, substantially as described. 85

2. In a seal-lock, a barrel carrying a seal-holding device, a plunger arranged to move therein and carrying a second seal-holding device, between which devices a breakable seal is adapted to be held, and a lock for holding said plunger in its inner position until the same is rotated to separate the seal-holding devices laterally and thereby break the seal, substantially as described. 95

3. In a seal-lock, a barrel carrying an interlocking pin, a plunger moving therein carrying an interlocking pin, between which interlocking pins a breakable seal is adapted to be held, and a lock for holding said plunger in its inner position until the same is rotated to separate the interlocking pins laterally and thereby break the seal, substantially as described. 105

4. In a seal-lock, the combination with a breakable seal having openings in the ends surrounded by fragile and breakable walls, 115 of seal-holding parts arranged to be approached to engage said openings, a lock for holding said parts in the approached position to lock the seal, and means for permitting the relative movement of said parts transverse to the axis of said seal to break said fragile walls and unlock said parts, substantially as described. 120

In witness whereof I have hereunto subscribed my name in the presence of two witnesses. 125
